UNITED STATES PATENT OFFICE.

ERNEST B. PRIEBE, OF INWOOD, NEW YORK, AND DANIEL P. MINER, OF PROVIDENCE, RHODE ISLAND; SAID MINER ASSIGNOR OF HIS UNDIVIDED ONE-HALF INTEREST TO WARREN C. DRAKE, OF INWOOD, NEW YORK.

FURNACE GRATE.

Application filed June 25, 1921. Serial No. 480,394.

This invention is a novel furnace grate adapted for use in connection with automatic stokers and being herein illustrated in connection with an underfeed stoker for

5 a boiler furnace. The general objects of the present invention are to afford a furnace grate and stoker of greater efficiency in operation and superior strength and durability in construction. A particular object 10 is to minimize the difficulty of the sifting of ashes through the grate into the wind box, which has been quite pronounced in certain types of stokers. Another object is to improve the operation and efficiency of 15 the furnace by perfecting the manner and means of air distribution. Another specific object is to afford a novel and advantageous system of twyers for a furnace grate. Other and further advantages of 20 the present invention will be made to appear in the hereinafter following description of one form of embodiment thereof or will be apparent to those skilled in the art.

25 To the accomplishment of the objects and advantages mentioned the present invention consists in the novel furnace grate and stoker herein described and illustrated and the novel features of arrangement, combination, construction and operation thereof.

In the accompanying drawings Fig. 1 is a longitudinal section of a multiple retort furnace and stoker embodying the principles of the present invention.

35 Fig. 2 is a transverse section taken on the vertical line 2—2 of Fig. 1.

Fig. 3 is a perspective view on an enlarged scale showing in detail the construction of the extension grate.

40 Fig. 4 is a transverse section taken on the inclined line 4—4 of Fig. 1.

Although the invention might be applied to furnaces and grates of different kinds and types it is herein shown applied to the 45 multiple retort type illustrated in prior patent of Priebe 1,360,250 of November 23, 1920. Certain illustrated devices are not herein claimed to be novel, being well known con-

structions not requiring detail description, for example the coal infeeding means as 50 shown in Fig. 1 being similar to that shown in said prior Priebe patent.

Referring to the details of the herein illustrated embodiment of the present invention, the combustion chamber of the furnace is 55 shown as bounded by the usual wall 7 at the front, bridge wall 8 at the rear and side walls 9, 9.

The illustrated structure possesses the advantage of minimizing sifting into the wind 60 box, also a very advantageous and thorough air distribution into all of the fuel bed overlying the grates, this greatly improving the efficiency of combustion. In addition to these advantages the feature of the present 65 invention involving a certain amount of looseness and play between the different grate bars prevents any damage from expansion and contraction of the metal; the structure has an elasticity or self yielding 70 quality which takes care of the difficulties frequently involved in the expansion of the metal. Another and very important advantage of this invention is the protection 75 of the grate bars by maintaining them relatively cool. This is due to the mode of air travel, which passes horizontally through the spaces between the inclined grate bars and therefore has an extended length of travel in contact with the metal. The cooling effect is therefore applied more efficiently 80 and completely than in a different arrangement, and the heat which is produced at the outer surface of the grate bars is the more readily conveyed away and dissipated, 85 thus minimizing the burning away and destruction of the metal of the grate bars.

The general structure of furnace and stoker is similar to that disclosed in the prior Priebe patent, above mentioned, and 90 therefore reference to many details will be omitted. The front wall 7, bridge wall 8 and side walls may be as shown. The fuel bed 15 is supplied from an exterior coal hopper 16 from which the fuel is underfed 95 into the furnace by a ram 17 operated and

controlled by mechanism 23. The fuel passes into a series of longitudinal retorts 25, and is thrust upwardly forming a bed overlying the entire grate, and eventually 5 passing downwardly to the dumping grate 26, which periodically discharges the refuse into the ash pit 27. The retorts are in the form of inclined troughs extending downwardly toward the rear, and each re- 10 tort may contain one or more distributing rams or pushers 91, maintaining the fuel in gradual progress toward the rear. The retorts are formed between a series of twyer boxes 92 above each of which is a bank of 15 twyer members or blocks 93, shown the same as in the prior Priebe patent, and overlying these upstanding twyer members are a series of overlapping cap pieces 94, which complete the twyer construction between the 20 retorts. The main air duct 95 leads to the compartmented wind box 96 which supplies air both to the twyer boxes 92 and to the terminal grate section 97, which may be termed an extension grate as it follows after 25 the main grate and supports the fuel which has passed beyond the retorts on its way to the dumping grate.

The present invention is shown applied herein, not to the main grates, but to these 30 extension grates 97. The extension grate is made up of a series of groups of grate members or bars, and the groups are relatively reciprocated during combustion, the upper side of the movable portions sliding beneath 35 a coal plate 98 which in turn is located directly beneath the lower ends of the system of twyer members 93 and cap pieces 94, that is, at the rear or discharge ends of the retorts, from which point the extension grate 40 members extend in the same longitudinal direction as the retorts, toward the dump grate and bridge wall. The combustion in this part of the furnace, between the main grate and the dumping grate, is of substantial 45 importance and the present improvement adds material efficiency thereto.

The grate bars 75^a in one group and the similar grate bars 75^b in an adjacent group are generally similar. Each is shown as 50 having the rightward ribs 83 and leftward ribs 84, giving recesses and affording the interengaging structure, the fit being sufficiently loose to give horizontal air passages of substantial length from the underside of the 55 slanting bars to the upper side thereof. Since all of the bars 75^a of one group move in unison they are identical and the upper ends of all of them are flush and located directly beneath the coal plate 98. All of the 60 grate bars of each group are connected permanently together by a rod 99 which also connects all of them to the upstanding brackets or flanges 100 of an underlying support 101 so that each two adjacent groups 65 while interengaged with each other through

the ribs 83 and 84 are independent in regard to longitudinal reciprocation. The stoker may be operated so that alternate groups remain stationary while those between are reciprocated, but we prefer, that as one group 70 75^a moves forwardly the adjacent group 75^b moves rearwardly thus giving alternate opposite reciprocating motions, which assist in the advance of the fuel bed as it passes over the extension grates on the way to the 75 dumping grate. Each of the supports 101 is shown as having downward flanges 102 by which it is slidably fitted upon the underlying guiding means or stationary members 103 of the furnace structure. A suitable reciprocating means consists of a rock shaft 104 connected by arm 104^a and link 104^b with the lugs 102, and an actuating arm 105 moved forwardly and rearwardly by a connecting rod 106 extending to an oscillating lever 107 at the exterior front of the machine, which is pivoted at 108 and receives its actuation from the operating mechanism 23.

The air of combustion passes from the 80 wind box 96 into the auxiliary wind box 109 beneath the grate bars 75^a and 75^b, the air passing through a damper 110, controlled by an exterior handle 111. From the wind box 109 the air enters the fuel bed between the 95 respective grate bars of the extension grate.

It will thus be seen that we have described a furnace grate embodying the principles and attaining the objects and advantages of the present invention. Since many 100 matters of arrangement, combination, design and detail may be variously modified without departing from the principles involved, it is not intended to limit the invention to such matters except in so far as specified in the appended claims.

What is claimed is:

1. In a furnace grate having a plurality of parallel inclined fuel retorts discharging longitudinally, the combination therewith of an extension grate receiving burning fuel from the retorts and conducting it longitudinally towards a rear dumping point, consisting of numerous downwardly inclined longitudinal grate bars, with their upper sides in downwardly trending step formation, each bar having a larger vertical depth than either its transverse thickness or the height of each step and constructed with horizontal ribs at its two sides projecting into the spaces between the ribs of the adjacent grate bars to provide numerous air passages between the ribs and bars into the fuel bed.

2. In a furnace grate having a plurality of parallel inclined fuel retorts discharging longitudinally, the combination therewith of an extension grate receiving burning fuel from the retorts and conducting it longitudinally towards a rear dumping point, consist-

ing of numerous downwardly inclined and loosely assembled solid cast grate bars, each having at its two sides staggered side ribs projecting into the spaces between the ribs of adjacent grate bars to afford numerous narrow air passages into the fuel bed, the upper surfaces of the bars and said ribs being arranged in downwardly trending stepped formation. In testimony whereof, we have affixed our signatures hereto.

ERNEST B. PRIEBE.
DANIEL P. MINER.
